JOHN L. MOHUN AND HENRY PIESCH, OF OMAHA, NEBRASKA, ASSIGNEES TO NATIONAL LOCK WASHER COMPANY, OF NEWARK, NEW JERSEY, A CORPORATION OF NEW JERSEY

CURTAIN FIXTURE

Application filed December 9, 1929. Serial No. 412,628.

This invention relates to curtain fixtures that are used in connection with windows of railroad cars, and has for its object to improve on the construction shown and described in the pending application, Serial No. 412,608 filed on even date herewith.

In said pending application the two brake rods that were operated in connection with the shoes or members that contacted the sides of the window casing, were each urged by spring means outwardly so as to cause said members to bear with more or less force against the sides of the window casing, but the present improvement does away entirely with any spring means immediately associated with the brake rods and accomplishes with a single spring the functions heretofore performed by the two springs and also cooperates in the adjustment of the tension of said shoes or members against the sides of the window casing.

The present invention has nothing whatever to do with the construction or operation of these shoes or members but aims solely to effect and regulate their pressure against the sides of the window casing without changing the distance between said shoes or members. Accordingly the drawings illustrate two styles of curtain fixtures that are so similar in structure and operation that this invention is applied thereto in the same manner in each instance, and each style will be described somewhat in detail in order that the character of the invention and its ready adaptation to both styles will be fully understood.

In the accompanying drawing

Figure 1 is a front elevation partly broken and sectioned illustrating our improvement applied to one style of fixture.

Figure 2 is a section at the line 2-2 of Figure 1—

Figure 3 is a partly broken and sectioned elevation showing a modification of our invention, and

Figure 4 is a view similar to Figure 1 but showing the invention applied to another style of fixture.

Similar numerals of reference denote like parts in the several figures of the drawing.

Referring particularly to Figures 1, 2 and

3, 1 is the hollow bottom bar made of an integral piece of steel whose edges are at the top of the bar between which edges the lower part of the curtain 2 is suitably clamped, as shown and described in our pending application Serial No. 412,627 filed on even date herewith, and, as the securing of the curtain to the bottom bar has nothing to do with the present invention, no description thereof will be given herein.

3 is the usual spring roller around which the curtain is wound at the top and which always exerts a tendency to wind the curtain.

4 are blocks which are secured within the bar 1 near the outer ends thereof in any suitable manner, as by screw 5, shown in the instance of one of the blocks at Figure 2, and 6 are what will be termed "shoes" that are elongated and have threaded sleeves 7 that extend inwardly therefrom and are driven upon threaded posts 8 that project outwardly from the end blocks 4.

9 are blocks that are movably disposed within the bar 1 in spaced relation to each other and also to the end blocks 4, and these blocks 9 are in the central zone of the bar 1.

10 are brake rods which extend loosely through the blocks 4 and have threaded connection at their inner ends with inward extensions 11 of the blocks 9 to which extensions 11 pinch bars 12 may be secured, which bars extend outwardly through openings 13 in the bar 1 so as to be readily available for use outside the bar.

It is important to note that, in the construction shown in the pending application Serial No. 412,608, aforesaid, these brake rods pass loosely through the blocks 9, whereas, in the present instance, said rods are threaded with in said blocks.

The outer extremities of these rods 10 may be pivoted as at 14 to cams 15 that have lower tail projections 16 that are pivoted within the shoes at 17, so that it will be clear that the outward movements of these rods will force these cams against the floors 18 of the grooves at the sides of the window casing so as to hold the curtain in horizontal adjustments, while the inward movements of said rods will re-

lax the cams so as to enable the curtain to be readily adjusted.

19 is an elongated stem which passes loosely through one of the end blocks 4 and has a screw head 20 on its end immediately outside said block, and this stem has a threaded connection through one of the movable blocks 9 and passes loosely through the other block 9.

In the construction shown at Figure 1, this stem 19 is threaded at 21 and engages within a threaded portion of the nigh block 9, the stem immediately beyond this threaded portion 21 being reduced in diameter for convenience in assembly, a collar 22 being placed around this reduced portion of the stem and located against the shoulder formed by said reduction, while the outer end of the reduced portion of the stem extends loosely through the other block 9, and a coil spring 23 surrounds this reduced portion of the stem and is confined between the collar 22 and this last named block.

It will thus be clear that the force of the spring has a tendency to drive the nigh block outwardly, the reaction of said spring likewise tending to drive the other block outwardly, and this will, of course, cause the cams to bear with force against the floors 18.

By engaging the head 20 with a screw driver passed through the end of the bar 1 the stem 19 may be operated to drive its threaded portion further into the nigh block 9, thus compressing the spring, and causing said cams to bear with greater force against the floor 18, while the turning of the stem in the reverse direction will allow the spring to expand and relieve the pressure of the cams against the floors 18.

Referring to the construction shown at Figure 3, the extremity of the stem 19 is threaded as seen at 24 and engages within a threaded portion in the further block 9, the stem passing loosely through the nigh block 9, and the coil spring 23 surrounds the stem 19 and is confined between the nigh block 9 and a collar 25 that is fixed on the stem 19 so as to be spaced from the further block 9.

In this last named construction it will be noted that if the stem is operated to drive the threaded portion 24 further along through its associated block 9, this collar 25 will be moved nearer said block and therefore the tension on the spring will be relaxed, and, on the other hand, if the stem be operated to withdraw the threaded portion 24 through its associated block, this will cause the collar 25 to compress the spring and place a greater tension thereon.

It will be clear that the compression of the spring will cause it to react on both of the blocks 9, while its relaxation will likewise cause the tension on said blocks to be lessened, for the purpose hereinbefore described.

In the constructions above described, the

collars 22 and 25 are, in effect, shouldered portions on the adjusting stem 19, and it will be observed that in the constructions shown at both Figure 1 and Figure 3, the spring 23 is confined between a shouldered portion on this stem and the block 9 most distant therefrom, and it is therefore immaterial as to which of the blocks 9 has threaded connection with this stem 19.

A characteristic of the style of fixture shown at Figure 1 is that the shoes have threaded connection with the stationary blocks 4, and in adapting the fixture to a window casing the shoes are revolved in the direction necessary to cause the fixture to initially fit between the sides of the window casing, and this revolution must be communicated to the brake rods, for otherwise the latter would jam, and that is the reason why the rods are pivoted to the cams, but the rods are frequently free of all actual connection with the cams and have their outer ends bent at a right angle, as shown at b in Figure 1, in the instance of one of these rods, so that the revolution of the shoe will carry the brake rod with it.

Referring to Figure 4, the shoes are designated by the numeral 26 and are substantially solid with shanks 27 extending freely within hollow posts 28 leading from the blocks 4, and the outer ends of the rods 10 likewise pass loosely through these blocks and are secured to said shanks, as by a threaded connection therewith, and preferably pins 29 are driven through these shanks and project into elongated slots 30 formed in opposite sides of the posts 28 for the purpose of keeping the shoes vertical. But this pin and slot provision is not always utilized since it is not essential.

Otherwise, than as just described, this fixture shown at Figure 4 is identical with that shown at Figure 1, the only difference being that in the Figure 1 construction the shoes are stationary so far as spring influence is concerned, but carry members that are acted upon by the springs, while in the construction shown at Figure 4 the shoes themselves are the members that are directly influenced by the springs. But, in either construction, there is frequently an excessive or an inadequate pressure of the cam or shoe members against the grooves at the sides of the window casing, in the one instance making the operation of raising or lowering the curtain unnecessarily difficult, and in the other instance causing the spring in the roller 3 to overcome the friction of the members that bear against said grooves, so that the curtain cannot be maintained in a lowered position.

It is therefore very essential that some means should be provided for readily adjusting the tension of this spring 23.

While pinch bars have been shown and described in connection with the brake rods,

they are not necessary and may be omitted, since the adjustment of the tension of the spring element may readily be made so that the curtain can be raised and lowered by 5 grasping the lower edge of the curtain and pushing it up or pulling it down, and therefore the invention is not limited in this respect. But it is preferred to use the pinch bars since their function is well understood 10 and no attention need be given to nicety of adjustment of the tension of the spring element.

The object of this invention being solely to regulate the pressure of the shoes or parts 15 carried thereby against the side grooves in the window casing without changing the distance between said shoes or parts, the actual construction and means employed for effecting a pressure against the slidable 20 blocks and brake rods, whereby the shoes are always resiliently forced against the ways in the sides of the window casing, is immaterial and has nothing to do with the present invention, since it is merely necessary that some 25 spring means should be employed in connection with said movable blocks to normally force said blocks apart so as to effect the pressure of said shoes against said grooves and therefore the invention is not limited in 30 these respects.

What is claimed is:—

1. A curtain fixture for a window, comprising a bottom bar to which the lower edge 35 of the curtain is secured, blocks near the ends of said bar, members supported by said blocks and extending beyond the bar and adapted to track within suitable ways in the sides of the window casing, spaced movable blocks, brake rods extending loosely through 40 said end blocks and having operative connection with said members and secured at their inner ends to said movable blocks, and spring means acting upon said movable blocks and functioning to normally force the latter apart.

2. A curtain fixture for a window, comprising a bottom bar to which the lower edge 45 of the curtain is secured, blocks near the ends of said bar, members supported by said blocks and extending beyond the bar and adapted to track within suitable ways in the sides of the window casing, spaced movable blocks, brake rods extending loosely through 50 said end blocks and having operative connection with said members and secured at their inner ends to said movable blocks, spring means acting upon said movable blocks and functioning to normally force the latter apart, and means for adjusting said spring 55 means.

3. A curtain fixture for a window, comprising a hollow bottom bar made of metal within the upper edge of which bar the lower 60 edge of the curtain is secured, blocks fixed 65 within said bar near the ends thereof, mem-

bers supported by said blocks and extending beyond the bar and adapted to track within suitable ways in the sides of the window casing, spaced movable blocks within said bar near the central portion thereof, brake rods 70 extending loosely through said end blocks and having operative connection with said members and secured at their inner ends to said movable blocks, and spring means acting upon said movable blocks and functioning to 75 normally force the latter apart.

4. A curtain fixture for a window, comprising a hollow bottom bar made of metal within the upper edges of which bar the lower edge of the curtain is secured, blocks fixed 80 within said bar near the ends thereof, members supported by said blocks and extending beyond the bar and adapted to track within suitable ways in the sides of the window casing, spaced movable blocks within said bar 85 near the central portion thereof, brake rods extending loosely through said end blocks and having operative connection with said members and secured at their inner ends to said movable blocks, spring means acting 90 upon said movable blocks and functioning to normally force the latter apart, and means for adjusting said spring means.

5. A curtain fixture for a window, comprising a bottom bar to which the lower edge 95 of the curtain is secured, blocks fixed within said bar near the ends thereof, members supported by said blocks and extending beyond the bar and adapted to track within suitable ways in the sides of the window casing, spaced movable blocks within said bar near the central portion thereof, brake rods extending loosely through said end blocks and having operative connection with said members and threaded at their inner ends within 100 said movable blocks, an elongated stem passing loosely through one of the movable blocks and having a threaded connection with the other movable block, a shouldered portion rigid with said stem, and spring means 105 acting upon said movable blocks and functioning to normally force said members against said ways without changing the distance between said members.

6. A curtain fixture for a window, comprising a bottom bar to which the lower edge 110 of the curtain is secured, blocks fixed within said bar near the ends thereof, members supported by said blocks and extending beyond the bar and adapted to track within suitable ways in the sides of the window casing, spaced movable blocks within said bar near the central portion thereof, brake rods extending loosely through said end blocks and having operative connection with said members and threaded at their inner ends within 115 said movable blocks, and spring means between said blocks and acting to hold said members in resilient contact with said ways.

7. A curtain fixture for a window, com-

prising a bottom bar to which the lower edge of the curtain is secured, blocks fixed within said bar near the ends thereof, members supported by said blocks and extending beyond the bar and adapted to track within suitable ways in the sides of the window casing, spaced movable blocks within said bar near the central portion thereof, brake rods extending loosely through said end blocks and having operative connection with said members and threaded at their inner ends within said movable blocks, spring means between said blocks and acting to hold said members in resilient contact with said ways, and means for adjusting said spring means.

8. A curtain fixture for a window, comprising a bottom bar to which the lower edge of the curtain is secured, blocks fixed within said bar near the ends thereof, members supported by said blocks and extending beyond the bar and adapted to track within suitable ways in the sides of the window casing, spaced movable blocks within said bar near the central portion thereof, brake rods extending loosely through said end blocks and having operative connection with said members and threaded at their inner ends within said movable blocks, an elongated stem passing loosely through one of the movable blocks and having a threaded connection with the other movable block, a shouldered portion rigid with said stem, and spring means interposed between said movable blocks and functioning to exert a pressure against said shouldered portion and slidale block through which said stem freely extends.

In testimony whereof we affix our signatures hereto.

JOHN L. MOHUN.
